CONTROLLER FOR PRINTING PRESSES OR
THE LIKE

Harold L. McCleery, Downers Grove, and Allan J. Cline, Chicago, Ill.; said McCleery assignor to said Cline

Continuation of application Serial No. 392,801, September 16, 1929. This application April 25, 1934, Serial No. 722,392

10 Claims. (Cl. 172—179)

The present application is a continuation of application Serial Number 392,801 filed September 16, 1929.

Our invention relates to electric controller systems, and has for its main purpose the provision of a controller particularly adapted for newspaper printing presses of the unit type in which a plurality of motors are employed for driving the units and folders which are ordinarily arranged in a continuous row and are divisible into groups forming presses of desired capacity.

The control provided by the invention is well suited, though not limited, to the type of press drive shown in Patent No. 1,734,077, to Allan J. Cline, in which individual motors are provided for the several printing units and folders of the press.

An important object of the invention is to provide a device for facilitating the transfer from high to low voltage when the press is slowed down. As will later appear, a high voltage is used for normal running and a much lower voltage for certain occasions, such for example, as when the cylinders are being plated or when the web is being threaded through the press. After dropping out the high voltage contactor in slowing down, the drive motors for a time may continue to run fast enough to generate a counter E. M. F. of higher voltage than that of the low voltage circuit and if the transfer to the low voltage circuit were made under such conditions, serious damage might be caused such as short circuiting the motors through the low voltage generator and causing excessive regeneration which might cause damage to the press, or, in any event break the webs. The device above referred to prevents the closing of the low voltage circuit until the counter E. M. F. generated by the motors is reduced to substantially the E. M. F. of the low voltage line.

A further object of the invention is to provide in a control system of this character a novel means for dynamic braking.

A still further object of the invention is to provide in conjunction with the master switch which is employed for controlling all the motors, means for interlocking the master switch and stop relay, thus insuring that the switch arm will be returned to the off position in all cases after operation of the stop relay before any units of the press can again be moved. This is an important safety feature, as will later appear.

Various other objects and advantages of the invention will be apparent as it is better under-

stood from the following description, which, taken in connection with the accompanying drawings, discloses a preferred embodiment thereof.

Referring to the drawings:

Figure 1 is a diagrammatic view, illustrating a printing press and control devices therefor embodying our invention;

Figure 2 is a diagrammatic view of a master panel for controlling the press, the same being shown in rear elevation;

Figure 3 is a straight line wiring diagram for the master panel;

Figure 4 is a diagram of the same type illustrating the connections to the motors of two press units;

Figure 5 is a similar diagram illustrating the necessary circuit for commutating the individual motor fields to the exciter generators of the master control panels; and

Figure 6 is a diagram illustrating the connection of the push buttons and the commutating thereof to either one of the master panels.

To illustrate our invention we have shown on the drawings a diagram of the preferred control arrangements and devices for operating a newspaper printing press, the printing units of which are numbered 1 to 7 inclusive and the folder units of which are numbered F¹ and F² in Fig. 1, diagrammatic illustrations of two master panels 11 and 12, and suitable connections for connecting the master panels to the press.

The units 1 to 7 may be a part of the series of the printing units of the press and are each provided with a driving motor 14. The folders F¹ and F² are similarly provided with driving motors 15. Wires for controlling the motors 14 and 15 communicate with junction boxes 16, through suitable conduits 17. Push button outlets 18, which may be mounted adjacent or on each of the press units also communicate electrically with the junction boxes 16 through a conduit 19. All of the electrical connections to the motors 14 and push button outlets 18 communicate with a switch box 22 through a conduit 21. The switch box 22 may contain any type of tumbler or multiple switch, or may contain individual switches for directing the various circuits to the master panels. In the present instance we have shown two master panels and in this embodiment double throw switches are required to direct the current either through conduits 23 for connection with the master panel 11, or conduits 24, for connection with the master panel 12. A high voltage line 25, which in the

present instance is a 230 volt line, and a low voltage line 26, which in the present instance is a 40 volt line, communicate with both of the master panels.

5 Motor generator sets 78, 79 hereinafter described, are connected respectively into the master panels 11 and 12 as diagrammatically shown in Fig. 1.

The row of press units and folders may be 10 divided into a number of complete presses, each comprising a folder and a selected number of press units associated therewith. In accordance with our invention, the individual drive motors for the folder and each of the press units comprising an individual press, are adapted to be controlled from one main control station of which two, identified by the reference characters 11 and 12, are shown in the drawings for purposes of illustration. The individual presses thus consist 15 of one folder and a selected number of press units, together with their individual drive motors, and a main control station, and the operation of such a press may be controlled from a single push-button station, as the station 18, associated with 20 the folder of the press.

As shown in Fig. 1, any individual press may 25 be controlled from either of two main control stations to provide for emergencies such as a mishap to the electrical apparatus of one of the control stations, but when operating, each press includes but one folder and one main control station, as above described.

Each master panel will preferably consist of 30 an upper section or master switch section 32, a lower or main control section 33 and a terminal board 33' (Fig. 2). The upper section 32 supports a motor operated face plate or master switch 31, a stop relay 34, two poles 35 up, and one pole 36 down, a low voltage relay 37, two poles 38 up, and one pole 39 down, a slow relay 41, two poles 42 up, a paster relay 43, two poles 44 up, a generator voltage relay 45, single pole 46 up, an inch relay 47, single pole 48 up, an increase relay 49, single pole 51 up, a decrease relay 52, single pole 53 up, a safe relay 54, single pole 55 down, a three-point paster dial switch 56, and a three-point torque switch 57.

The lower section or main control panel 33 has 50 mounted thereon a high voltage or 230 volt line contactor 58, two poles 59 up, two interlocks 60, and an interlock 138; also a low voltage or 40 volt line contactor 61, two poles 62 up, and two interlocks 63; three accelerating contactors 64, single pole 65 up; a dynamic braking contactor 66, single pole 67 up with normally open full field interlock 100; a transfer relay 68, a slow down contactor 69, single pole 70 up, and double pole line knife switches 71 and 72. All of the above mentioned devices are electrically interconnected as will be later described. The apparatus mentioned above is also illustrated by a straight line diagram, Fig. 3, with corresponding numerals.

Fig. 4 shows two of the individual unit motors 65, resistance elements 73, 74, and 75 for each motor, series field windings 76 and 77, and double throw switches 80, for connecting the respective motors with either one of the master panels 11 or 12 shown in Fig. 1.

70 In Fig. 5 an exciter motor generator set is shown, the motor being indicated at 78 and the generator at 79. Shunt field windings 81 and 82 for the individual drive motors 14 and 15 are connected as shown in Fig. 5, and double pole switches 83 are employed to associate said field

windings 81 and 82 with the motor generator set 78, 79 of one or the other of the master panels 11 or 12.

In Fig. 6 the usual push buttons required for 10 operation of the printing press are indicated and include a paster button 84, a safe-run button 85 having a circuit closing push button for preventing press operation and a circuit opening push button for permitting press operation, 15 said two last mentioned push buttons being mechanically inter-connected, a stop button 86, a decrease button 87, an inch button 88, and an increase button 89. Double throw switches 90 are included in the circuits with the above mentioned push buttons to provide a means of connecting them with either of the master control panels. The switches 80, 83 and 90, indicated in Figures 4, 5, and 6, are all preferably mounted 20 in the switch box 22 (see Fig. 1) of the press unit controlled thereby.

As previously stated the motor operated face plate 31 of the master control panels controls the sequence of certain relays and contactors and regulates the generator fields of the small motor generator sets above mentioned. The generator 25 of these small sets has an adjustable armature voltage, the variation of which is directed by the master switch for varying the voltage impressed upon the fields of the individual drive motors 14 and 15, which are connected in parallel so 30 that each individual motor will have the correct field strength for parallel operation at any desired speed. This makes it possible to omit a field rheostat formerly required on each individual motor and facilitates complete control 35 of the individual motors by the master switch.

In the diagram we have shown all of the 40 circuits on the master panel with the apparatus positioned ready for the starting of the press and with the line switches 71 and 72 open. The arm 101 of the master switch 31 in starting position rests on contacts 102, 103, 104, and 105, but is shown in Fig. 1 as moved therefrom for the sake of clearness. Said arm is adapted to be moved in a counterclockwise direction (viewing Fig. 2) for starting and speeding up the operation of the press, and in a clockwise direction for slowing down or stopping the press. The actuating means illustrated is a small split field motor 106, the shaft of which carries a pinion 107, which meshes with a gear 108 on a shaft 109, which may be mounted in any suitable bearings and is connected to and adapted to transmit motion imparted to the gear 108 by the motor pinion, to a worm 111, engaging a worm gear 112, carrying the arm 101 mounted on a transverse shaft 113.

In starting the press the main line switches 71 and 72 are closed. This starts the motor 78 of the field motor-generator set, the generator field circuit being from X to the master switch arm 101, through segment 127, contact 105, and the field of the generator 79 to Y. When the generator voltage builds up, relay coil 45, which is connected across the generator (Fig. 5), is energized and closes contacts 46 which are in circuit with the upper contacts 38 of the low voltage relay 37. It will be understood that each of the run buttons 85 must be depressed before the press can be started, as depression of any one of the safe buttons will energize the safe relay 54, from X through the safe button to 29 through safe relay coil 54 to Y, preventing operation of the press in manner which will hereinafter appear. With the master switch arm 101 in the 75

normal or off position, the control mechanism is in condition to operate the press for inching and threading the web. In the off position the arm 101 contacts segment 104 and the low voltage relay 37 is energized from X through the master switch arm 101 to segment 104, through the coil of relay 37 to 103a, through the normally closed contacts 36 of the stop relay 34, to Y. A holding circuit for the low voltage relay 37 is provided from X through the lower contact 38 of the low voltage relay, through the coil of said relay to 103a, through stop relay contacts 36 to Y, thus making it possible to move arm 101 off the reset segment 104 without deenergizing low voltage relay 37. The back contact 55 of the safe relay 54 is closed, and depression of the inch button 88 (Fig. 6) will close a circuit from X through contact 55 to 10 through the inch button 88 to 222, through the high voltage or 230 volt interlock 60 to 20, through the low voltage or 40 volt line coil 61 to 17 through contacts 114 of relay 137 to 18, through one pole 38 of the low voltage relay 37 to 19, and through contact 46 of generator voltage relay 45 to Y, for energizing the motor circuits of the press units. Release of the inch button opens this circuit and deenergizes the motor circuit.

Current is supplied to the armature of press motor 14 from + on the low voltage line 26 to 2, through contacts 62 of the low voltage contactor to S₄, through series field resistances 76, 77, to the armature, then through resistances 73, 74, 75 to R, then through the other contacts 62 of the low voltage contactor to 4, and then through knife switch 72 to — on the low voltage line 26. Similarly, current is supplied to the armature of motor 14 from + on the high voltage line 25 to X, thence through the upper of the contacts 59 of the high voltage contactor to S₄, thence through series field resistances 76, 77, to the armature of motor 14, thence through resistances 73, 74, 75 to R, thence through the other contacts 59 of the high voltage contactor to Y, and thence to — through switch 71.

Pressing the increase button 89, closes the increase circuit from X to 80 through relay 49 to 81 through a protective resistance 115 to 82, through an increase limit switch 116 to 18, through the low voltage contact 38 of relay 37 to 19 and the generator voltage contact 46 of relay 45 to Y. The closing of this circuit closes contact 51 from X to 75, which energizes an increase field winding 117 to 76 of the pilot motor 106 to Y, which rotates the master switch arm 101 in a counter-clockwise or press-accelerating direction, effecting the necessary connections for increasing the speed of the press.

Forward movement of the master switch arm 101 makes contact with a segment 121, closing the inch button circuit of the press, which closes the low voltage main line contactor 61, X to 121 through contact 60 to 20 through coil 61 to 17 through contact 114 to 18 through pole 38 of relay 37 to 19, through contact 46 of generator relay 45 to Y, starting the press at slow speed, and by contact with a segment 122, closes a circuit through the 40 volt interlock 63 to 23, through the coil of the 230 volt line contactor 58 to 18, through the low voltage contact 38 of relay 37 to 19 and generator voltage contact 46 of relay 45 to Y which closes the 230 volt line contactor and thereby energizes the individual motors of the press units subject to the series resistance elements 73, 74, and 75 in the armature circuit of the motors 14 and 15 (Figs. 3 and 4). The

line contactors 58 and 61 are preferably electrically and mechanically interlocked to insure against the closing of both at any instant to avoid danger of a short circuit. As the master switch arm 101 moves forward, contact is made successively with segments 123, 124, and 125, closing the contacts 55 of the accelerating contactors 64 successively, thereby cutting out the resistance elements 75, 74, and 73 in the order mentioned, thus bringing the individual motors 14 and 15 up to their full field speed. Further movement of the arm 101 brings it into successive contact with contact buttons 126, one of which is connected to a segment 127 and the remainder of which are connected together through suitable resistance elements, together forming a step-up resistance 128 (Fig. 3). As the arm 101 makes successive contact with the buttons 126, it decreases the field voltage of the exciter generators 19 and in turn the field excitation of the unit motors 14 and 15, and further increases the operating speed of the press as the arm 101 advances.

Depression of the decrease button 87 closes a circuit from X to 70 through a decrease limit switch 129 to 73 and the decrease relay 52 to Y. Operation of the decrease relay 52 in turn closes a circuit through its contact 53 from X to 80 and a decrease winding 131 to 76 of the pilot motor 106 to Y, thereby causing a reversal of the direction of movement of the arm 101 and the dropping of all the connections established in the forward movement thereof.

The pilot motor 106 is preferably a motor of the split field type or a motor having a field winding adapted to cause rotation of the motor in one direction corresponding to the field winding 117, and a second field winding adapted to cause rotation of the motor in the opposite direction corresponding with the winding 131 (Fig. 2).

A segment 120 of the master switch 31 is provided with a sliding contact member 118, having a flexible wiper 119 extending into the path of the arm 101 (Fig. 2). The member 118 is manually adjusted on the segment 120 to a position determined by a running test, at which the press operates with the greatest efficiency and without undue danger or strain. When the arm 101 makes contact with the wiper 119, it shorts out the increase relay coil 49 and stops the pilot motor 106 by the circuit X on arm 101 to 81 on contact 119 through protective resistance 115 to 82 through limit switch 116 to 18 through contact 38 to 19 through generator contact 46 to Y, thus stopping acceleration and preventing further control of the press through the increase button, the short being made through the protecting resistance 115 (Fig. 3).

The depression of the stop button 86 closes X to 30, operates the stop relay 34, and closes a circuit through a coil 132 of said stop relay to 31a, through a protective resistance 133 to Y. The closing of this circuit actuates the stop relay 34 which establishes its own holding circuit through one of the poles 35, in closing, the circuit being from X through contact 39 to 70 through limit switch 129 to 73 through contact 35 to 30 through coil 132 to 31a, through protective resistance 133 to Y. The contact 36 of the stop relay 34, which is normally closed, opens when the above mentioned circuit is closed and thereby opens the low voltage relay circuit, dropping out the low voltage relay 37. The other of the two poles 35 of the stop relay 34 closes 75

a circuit from X to 50 through the interlock 63, of the low voltage or 40 volt line contactor 61 to 51', through the interlock 60 to 52' of the high voltage or 230 volt line contactor 58 through 5 dynamic braking contactor coil 66 to Y, and provides the dynamic braking for the press by closing contacts 67 of the dynamic braking contactor 66, thereby closing a circuit through a resistance element 134, associated with each of the 10 unit and folder motors 14 and 15, which shunts the motor armatures from A1 through selector 80 to 5, through dynamic contact 67 to B1, through resistance element 134 to A2. Dynamic braking is accomplished by short circuiting the 15 drive motor armatures through resistance element 134, and contacts 67 of contactor 66 whenever a stop button is depressed or an overload relay operates. A normally open interlock 100 operated by the dynamic braking contactor 66, 20 connected across the exciter generator field rheostat 126 provides full field on the drive motors for dynamic braking. No matter what operating position may be occupied by switch arm 101 when interlock 100 is closed, the generator 25 79 obtains full voltage from X through interlock 100 to 1 through segment 127, contact 105, and the field of the generator 79 to Y. Since the motor fields 81 are excited in turn by the generator 79 they also have full field provided for braking. The combination of a full field interlock to build up the generator voltage and in turn the generated armature voltage of the drive motors introduces a time element in the building up of 30 the drive motor voltage, which tends to keep the current peaks to a minimum and holds the current practically constant over the braking period.

When the low voltage relay 31 drops out as the result of the depression of the stop button 40 or the operation of the usual overload relay (not shown), the low voltage relay closes the decrease button circuit, causing current to flow from X through contact 39 of the low voltage relay 31 to 70, through the limit switch 129 to 73, through 45 coil 52 to Y, thus closing contacts 53 of the decrease pilot motor relay. The closing of said contacts 53 causes current to flow from X to 80 through the decrease field 131 and armature 106 of the pilot motor, causing the same effect as 50 that caused by the depression of the decrease button, namely, the return of the arm 101 to normal or off position as above described.

The circuit controlled by the paster button 84 is one of the usual type, having the function of 55 slowing down the press to permit making the paster, and need not be described in detail.

One difficulty in connection with dual voltage control for presses has been in transferring from the high voltage circuit to the low voltage circuit. 60 To accomplish this we employ, in the connection presently described, a current rectifier 135, which may be of any suitable type and is preferably a dry plate rectifier, similar to those used in battery charging and rectifying units. This device prevents the low voltage contactor 61 from picking up or actuating after the high voltage contactor 58 drops out until the main motor counter E. M. F. is equal to the opposing voltage of the low voltage line. In the present embodiment we accomplish this by connecting a protective resistance 136 (Fig. 2) across one pole 62 of the low voltage contactor 61 and across the other pole 62 of said contactor 61 connecting a relay coil 137, the rectifier 135 and an interlock 138, associated with the high voltage contactor 58. The

interlock 138 serves to keep this circuit open at all times except when the high voltage contactor is de-energized and to close the circuit through the above mentioned devices particularly during the period of transfer from high to low voltage. Closing of said interlock 138, which results from opening the contactor 58 while the press is running at high speed will establish a circuit from A1 through the motor series field, through the relay coil 137 to 8, through the rectifier 135 to 10 3, through said interlock 138 to 2, through one pole of the low voltage switch 72 to + through the low voltage generator armature circuit to -, through the other pole of the switch 72 to 4, through the protective resistance 136 to R, through the armature regulating resistance 75, 15 74, and 73 and back to the motor at A2.

If the main motor is generating a counter E. M. F. of higher voltage than the voltage of the opposing low voltage line circuit, current will flow 20 through this circuit opening the contacts associated with the relay 137 thus preventing operation of the low voltage contactor 61, and the poles 62 thereof, even though all other circuits are in a position to actuate the low voltage contactor 61. 25 When the counter E. M. F. of the main motor has reduced by coasting of the press to a value equal to the opposing low voltage circuit, no current will flow through the relay 137 which permits the contacts 114 thereof to close, and will in turn 30 close the low voltage contactor 61, and complete the low voltage power circuit to the press drive motors, the transfer being made at a time when the counter E. M. F. is substantially equal to the low voltage line current. 35

In order to insure that the master switch arm 101 is in off position and that the control of the stop button is absolute, so that once the stop button has been pressed, especially in emergency, it will be impossible for any person not knowing of 40 the emergency to control the press from any of the press units, we provide means for interlocking the low voltage relay and the stop relay circuits upon manipulation of the stop button so that each provides a holding circuit for the other, thus preventing control of either by the push button circuits, and means for releasing these interlocked circuits upon the arrival of the master switch arm at the off position. To accomplish this, the back contact 36 of the stop relay 34 is connected in 45 series with the coil winding of the low voltage relay 31, and the back contact 39 of the low voltage relay 31 is connected in series with the decrease limit switch 129, one of the poles 35 and the coil 132, of the stop relay 34 and the protecting resistance 133. The decrease limit switch 129 is opened by the arm 101 in arriving at the off position thus opening the interlocked circuits. The opening of said limit switch 129 opens the circuit from X through contact 39 to 10 through 50 limit switch 129 to 73, through contact 35 of stop relay to 30 through stop relay coil to 31, through protective resistance 133 to Y, thus de-energizing coil 132, thus opening one pole 35 and closing the back contact 36 of the stop relay 34. Closing the 55 back contact 36 of the relay 34 energizes the coil winding of the low voltage relay 31 through a circuit completed by the master switch arm 101 from + in contact with the contact button 102 through coil 37 to 103 through contact 36 to Y, 60 and opening the back contact 39 thereof, thereby cutting out the decrease limit switch 129 and resetting the circuit for normal press starting operation.

It is thought that the invention and many of its 65

attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

We claim:

10 1. In a control system for printing presses or the like, a high voltage circuit for operating speeds, a low voltage circuit for slow speeds, a motor operated on said circuits, contactors for closing said high and low voltage circuits respectively, and means operative upon opening of the high voltage contactor for opposing the incoming voltage of the low voltage circuit with the counter E. M. F. generated by the motor whereby to prevent closing of the low voltage circuit after operation of the motor on the high voltage circuit until the counter E. M. F. generated by the motor reduces to substantially the opposing E. M. F. of the low voltage line.

2. In a control system for printing presses or the like, a high voltage circuit for operating speeds, a low voltage circuit for slow speeds, a motor operated on said circuits, contactors for closing said high and low voltage circuits respectively, and means for preventing the closing of the low voltage contactor after operation of the motor on the high voltage circuit until the counter E. M. F. generated by the motor reduces to substantially the opposing E. M. F. of the low voltage line, said means including a relay coil, a normally closed contact in the low voltage circuit adapted to be opened by energizing said coil, and means for directing the incoming voltage of the low voltage circuit through said coil in opposition to the counter E. M. F. generated by the motor.

3. In a control system for printing presses or the like, a high voltage circuit for operating speeds, a low voltage circuit for slow speeds, a motor operated on said circuits, contactors for closing said high and low voltage circuits respectively, and means for preventing the closing of the low voltage circuit after operation of the motor on the high voltage circuit until the counter E. M. F. generated by the motor reduces to substantially the opposing E. M. F. of the low voltage line, said means including a rectifier through which the current may pass from said motor in the direction of the counter E. M. F., but not in the opposite direction.

4. In a control system for printing presses or the like, a high voltage circuit for operating speeds, a low voltage circuit for slow speeds, a motor operated on said circuits, contactors for closing said high and low voltage circuits respectively, and means for preventing the closing of the low voltage circuit after operation of the motor on the high voltage circuit until the counter E. M. F. generated by the motor reduces to substantially the opposing E. M. F. of the low voltage line, said means including a relay coil, a normally closed contact in the low voltage circuit adapted to be opened by energizing said coil, and a rectifier through which the current generated by the motor may pass to energize said coil so long as the counter E. M. F. is in excess of the E. M. F. opposed to it from the low voltage line, said coil being deenergized when said counter E. M. F. is substantially equal to the E. M. F. of the low voltage line, thereby permitting the low voltage circuit to be closed.

5. In a control system for printing presses or the like in which a plurality of drive motors are employed for operating the units and folders of the press, an exciter generator for supplying a control current to the fields of said motors, a 5 rheostat for adjusting the generator voltage, a dynamic braking contactor, and an interlock actuated by said dynamic braking contactor for building up the generator voltage as the press speed decreases thus maintaining a substantially 10 uniform dynamic braking current in the drive motor armature during the braking period.

6. A controller for printing presses or the like comprising in combination with a plurality of motors for driving the units and folders of the 15 press, an exciter generator for supplying a control current to the fields of said motors, a master switch for controlling all of said motors, said switch being movable through a plurality of operative positions, means including a stop button for stopping the press, and means whereby 20 press control is prevented after the stop button has been actuated until said master switch has been returned to its initial position.

7. A controller for printing presses or the like comprising in combination with a plurality of motors for driving the units and folders of the press, an exciter generator for supplying a control current to the fields of said motors, a high 25 voltage circuit for operating the motors at high speed, a low voltage circuit for low speeds, a low voltage relay and circuit, a stop relay and circuit, push button stations including stop buttons associated with the press units, means operable upon manipulation of any stop buttons for interlocking the low voltage relay and stop relay circuits, causing each to provide a holding circuit for the other, thereby preventing control of the press, a master switch including an arm movable through 30 a plurality of operative positions, and means 35 operable only upon the return of said arm to initial position for releasing said interlocked circuits to permit further control of the press from the push button stations.

8. A controller for printing presses or the like comprising in combination with a plurality of drive motors, a master control device including a field exciter for varying the field strength of said motors simultaneously, a plurality of sources of voltage for said motors and control 45 devices whereby a low voltage may be employed for slow running of the press, as for plating the cylinders or threading the paper, and whereby high voltage may be employed for operating 50 speeds, said motors being subject to control by 55 said master control device when operating on either high or low voltage.

9. In a control system for printing presses or the like, a high voltage circuit for operating speeds, a low voltage circuit for slow speeds, a 60 motor operated on said circuits, contactors for closing said high and low voltage circuits respectively, and means for preventing the closing of the low voltage circuit after operation of the motor on the high voltage circuit until the counter E. M. F. generated by the motor reduces to substantially the opposing E. M. F. of the low voltage line, said means including a control 65 relay for the circuit of the low voltage contactor, and an energizing circuit for said relay connected in series with the motor, said circuit including a rectifier arranged to allow said relay to become energized to hold the low voltage contactor open so long as the voltage of the current 70

generated by the motor exceeds the voltage opposed to it from the low voltage line.

10. In a control system for printing presses or the like, a high voltage circuit for operating speeds, a low voltage circuit for slow speeds, a motor operated on said circuits, contactors for closing said high and low voltage circuits respectively, and means for preventing the closing of the low voltage circuit after operation 5 of the motor on the high voltage circuit until the counter E. M. F. generated by the motor reduces to substantially the opposing E. M. F. of the low voltage line, said means comprising a relay including a coil and a normally closed contactor for controlling the circuit which energizes 10

the low voltage contactor, a rectifier connected in series with the motor and the coil of said control relay, and an interlock connected in series with said rectifier and relay coil and adapted to close the circuit through said rectifier and relay coil upon opening of a high voltage contactor, said rectifier serving to allow current generated by the motor to flow through said coil to hold the low voltage circuit open so long as the voltage of the current generated by the motor exceeds the voltage opposed to it from the low voltage line. 15
